JUSTIN O. SCHWARZ, OF NEW YORK, N. Y., AND GUSTAV BJORKLUND, OF WEST NEW YORK, NEW JERSEY.

PNEUMATIC ACTION.

1,398,469.

Specification of Letters Patent. Patented Nov. 29, 1921.

Application filed October 6, 1917. Serial No. 195,193.

To all whom it may concern:

Be it known that we, JUSTIN O. SCHWARZ, a citizen of the United States, residing at New York city, N. Y., and GUSTAV BJORKLUND, a subject of the King of Sweden, residing at West New York, N. J., respectively, have invented certain new and useful Improvements in Pneumatic Actions, of which the following is a specification, reference being had therein to the accompanying drawing.

Our invention relates to improvements in pneumatic actions for player pianos and has particular reference to pneumatic action adapted for use in a grand piano.

Referring to the accompanying drawing indicated as Figure 1, we have illustrated in side elevation with parts broken away and partly in cross section, an application 20 of our invention to a grand piano.

2 indicates the key bottom and 3 the key with a suitable form of piano action above the same. 4 indicates the pneumatic and 5 a bell crank form of lever pivoted at 6 upon the block 7 and pivotally connected at the top by a wire 8 to the pneumatic 4 at 9 as shown. The lower end of the bell crank lever is provided with a suitable striker piece 10, adapted to lift the block 25 11 secured at the back of the key 3. 12 indicates a wire screw in the block 11 bent to clear the lever 5 and adapted to lift the damper lever 13 pivotally mounted at 14 and normally retained in the position shown 30 by the light spring 15 secured in the flange 16 upon the fixed rail 17. At the outer end of the damper lever 13 is pivotally mounted the block 18 provided with the wire 19 attaching the damper 20 through the guide 35 21. The stop 12 is beneath the hammer 13 so that when the pneumatic 4 is collapsed, the bell crank lever 5 is drawn leftwardly 40 at the top upon its pivotal bearing 6, lifting the block 11 by the striker 10 at the 45 back end of the key 3 which in turn lifts

the damper lever 13 clearing the piano string 22 which is thereupon struck by the hammer 23 through the piano action above the key 3 in the same manner as if actuated manually by striking the front end of said 50 key.

The piano action itself forming no part of this invention, it is not necessary to specify it in detailed construction and the pneumatic action is susceptible of application to various forms of piano actions and the pneumatic action itself may be changed in details in construction and arrangement without departing from the spirit of invention as claimed.

We claim:

1. In a piano and player action of the class described, an actuating pneumatic and key in front of the same, a bell crank pivoted between said pneumatic and said key whereby said action may be operated by said key or by said pneumatic through said bell crank and said key, said pneumatic, key and bell-crank substantially in horizontal alinement.

2. In a piano and player action of the class described, an actuating pneumatic and key in front of the same, a bell crank pivoted between said pneumatic and said key whereby said action may be operated by said key or by said pneumatic through said bell crank and said key, one leg of said bell crank substantially immediately under the inner end of said key, said pneumatic, key and bell-crank substantially in horizontal alinement.

In testimony whereof we hereunto affix our signatures in the presence of two witnesses.

JUSTIN O. SCHWARZ,
GUSTAV BJORKLUND.

Witnesses:

RELA K. CHABAM,
CHAS. BIANCO.
